UNITED STATES PATENT OFFICE

JOHN KARMAZIN, OF DETROIT, MICHIGAN

METHOD OF FORMING RADIATORS

Application filed July 3, 1924. Serial No. 723,860.

This invention relates to radiators suitable for use with internal combustion engines using cooling water, and particularly to radiators of the type disclosed in my pending application Ser. No. 641,850.

Radiators for water cooled internal combustion engines require the passage of water in one direction through one set of passages, and the passage of air in a different direction through other passages. For high efficiency it is desirable to have low resistance to air flow and also to the flow of water, and yet to divide up the circulating water and air into sufficiently small streams so that the water may be cooled rapidly, the heat thus generated being conducted to the air through thin metallic walls. It is of great importance that each part of the radiator be active in distributing this heat.

20 There are two principal types of radiators; one the honey-comb type of radiator, made up of corrugated strips suitably spaced apart to form a conduit for the water, the other being the tube type made up of a number of spaced flat sheets of metal through which are passed a number of tubes to conduct the cooling water. The assembly of radiators of this type which have been made hitherto has been found to be a very expensive process.

30 The radiator disclosed in my application above identified resembles generally the fin and tube type of radiator but it is constructed along lines differing widely from radiators as they have been made prior to my invention.

35 Said radiator comprises a stack of superposed elements, each comprising tapering tubular projections, separated by a laterally extending fin which is integral with the tubes, the projections of one element being adapted 40 to telescope into the projections of the adjacent element, whereby continuous water tubes are formed.

One object of the present invention is to provide a machine and method for forming and assembling the elements of my improved radiator as described above.

A further object of the present invention is to provide a method for constructing a radiator from a strip of sheet metal.

50 A further object of the invention is to pro-

vide a method of radiator construction comprising the mechanical forming and assembling of radiator elements.

A further object of the invention is to provide a method of manufacturing radiators according to which a strip of sheet metal is subjected to working such that it is brought to a condition wherein parts of the sheet have become transverse tubes adapted to conduct water, and to assemble sections of the strip so formed into a radiator by telescoping said tubes together to form continuous water conduits through the assembled strip sections.

A further object of the invention is to provide a method of manufacturing radiators according to which a strip of sheet metal is progressively deformed to provide transverse tubes without materially thinning or weakening the sheet and to assemble the sheet so formed into a radiator.

A further object of the invention is to provide a method of manufacturing radiators according to which interchangeable parts are made and assembled in such a way as to provide a plurality of transverse tubes.

With these and other objects in view, my invention consists in novel processes, which will be hereinafter described and which are illustrated in the drawings, said drawings illustrating one type of machine by which my improved process may be practiced.

In the drawings:

Figure 1 is a longitudinal elevation of a machine embodying my invention.

Figure 2 is a detail of the element cutting devices.

Figure 3 is a detail of the automatic clutch controlling device.

Figure 4 is a plan view of the machine shown in Figure 1 certain part being broken away for greater clearness.

Figure 5 is an elevation of the element forming and feeding devices.

5 Figure 11 is a front elevation of an assembled radiator.

10 Figure 12 is an enlarged detail view of a portion of the radiator.

15 My invention contemplates the formation from a strip of material preferably metal such as brass or copper, of a strip of radiator element forming material, comprising a flat fin portion having integral tubular projections extending therefrom. Such a strip in the process of formation is illustrated 20 in Figures 8 and 9, the strip being indicated generally by the numeral 15. The machine which I have illustrated in the drawings as best adapted for carrying out my process comprises a strip deforming tube forming and 25 punching machine, a device for supporting a roll of strip material to be fed to the machine, a feeding device, means for cutting the formed strip into elements of a predetermined length, means for receiving and stacking 30 the elements so formed, and means for compacting the stack of element into a radiator. The strip deforming and punching machine, by which a strip of flat material is formed into a strip of radiator element forming material will be first described.

35 The machine frame comprises a supporting base 16 (Figure 1) carried on pedestals 17, to which base are secured uprights 18, formed with bearings 19 adapted to receive the crank shaft 20. Power is applied to the crank shaft thru the belt wheel 21. Rotation of the crank shaft reciprocates a plunger 22 which is guided for vertical movement in the uprights 18.

40 The die mechanism which operates on the strip of sheet material 15 comprises downwardly extending forming punches and cutters carried by the upper male die member 23 on the plunger 22, and cooperating recessed female dies carried on the lower die 45 member 30 on the base plate 16. This die mechanism is shown in detail in Figures 6 and 7, in which the strip material advances from right to left. The plunger 22 carries the 50 upper die member or head 23 guided for vertical movement by rods 231. Secured to head 23 is a plate 24 which is drilled to receive and support the forming, punching and cutting tools 25, 26, 27, 28 and 29. Secured to 55 the supporting base 16 is a recessed plate 30 provided with recessed dies 261, 271, 281, and 291, in alignment respectively with the forming and other tools 26, 27, 28 and 29. Below the dies 261 are spring pressed plungers 31 adapted to lift the strip being formed 60 out of the die recesses, to permit the strip to be fed forward. An intermediate die member 241 perforated to permit the passage of plungers 25, 26, 27, 28 and 29 therethrough is 65 supported on the plate 30 by the spacing

blocks 241 and is secured thereto by the pins 301.

70 The tool 25 is simply a flat faced plunger, adapted to flatten or smooth out the metal strip 15 which is drawn out of shape as it approaches the first forming die 26. The function of dies 26 and 261 is to progressively form on and from the strip 15 rows of tubular projections transverse to the strip, and to accomplish this result without materially thinning and weakening the strip. To this end the first dies 26 which the strip encounters are adapted to form broad shallow depressions such as 33 in the strip, this operation 75 reducing or drawing in the width of the strip as clearly shown in Figure 8. The succeeding dies 26 progressively deepen and narrow the depressions 33, as shown in Figures 8 and 9 but do not further reduce the width of the strip, or materially reduce the thickness at 80 any point. In other words, the first operation displaces sufficient metal into the die 26 for the formation of the tubes, and the succeeding operations progressively re-form this metal into tubes of the proper size shape and 85 thickness. By thus starting with an initially 90 thin strip of metal 15 and forming the tubes 34 therefrom without materially thinning the strip it is possible to form watertight tubes of sound metal and still keep the weight of 95 the assembled radiator very low because of the initially thin strips of which it is composed.

100 The tools 27 and 271 are punches for removing or punching out the bottom of the fully formed tube. The tools 28—281 are punches adapted to perforate the strip between the tubes 25, for the purpose of securing improved circulation of air about the tubes, and the tools 29 and 291 are cutters 105 adapted to trim the edges of the strip and also to regulate the feed of the strip between reciprocations of the plunger head 23. The cutters are as long as the distance between centres of adjacent dies 26 and the forward 110 edges thereof, as defined by the spacing members 241, form stops 242 which halt the forward movement of the strip after each depression of the upper die member so that a strip as long as the distance between the die 115 members is cut off at each operation of the cutters and the strip is advanced the correct distance for the next forming step.

120 Since commercial roller strip metal such as my machine is adapted to use, is rarely or never of uniform thickness, one edge of the strip being almost invariably, slightly thicker than the other edge, I design the row of forming dies adjacent one edge of the strip to operate on metal of a slightly different thickness than the row adjacent the opposite edge 125 to provide for uniform operation of the die and uniform operation upon both sides of the strip.

130 The means for supporting the supply roll

of strip metal are constructed as follows. A bracket 37 is pivotally secured, to a projection 36 on the supporting base 16 and to the bracket 37 is pivoted an arm 38 carrying a supporting spindle 39 adapted to receive a roll of strip metal 40. The strip leaving said roll passes thru an oil bath 41 into which it is depressed by a roller 42, under a guide rod 43 and thence to the forming machine. As hereinbefore stated the dies of one edge of the forming machine are adapted for metal of greater thickness than the dies at the opposite edge i. e. by making one row plungers 26 adjacent one side of the die .001 inch longer or shorter than the plungers of the other rows. The supply roll must therefore be turned so that the thicker metal will be opposite the proper dies. It will be seen that this condition may be satisfied on the roller strips by turning the roll so that the strip will leave some rolls at the top and other rolls at the bottom, according to which is the thickest side of the strip when rolled or coiled on the spool. It is desirable, however that the strip shall leave the roll at approximately the same position relative to the forming machine and the oil bath. To secure this result the arm 38 which carries the strip roll is pivoted to the frame 37 and is adapted to be supported at different elevations by a stop pin 441 which can be inserted in either of two openings 44 and 45 in the frame 37. In the position of the arm 38 and roll 40 shown in the full lines in Figure 1 the stop 441 is inserted in opening 44, and the strip 15 is run off from the top of the roll with the thick part opposite the proper row of plungers 26, while in the position of these parts shown in dotted lines the arm is in engagement with the top in opening 45, and the bottom of the roll from which the strip is now fed is at approximately the same place as the top of the roll in the first position.

The means for feeding the strip of metal to the forming machine, and the strip of formed radiator building material from the forming machine to the cutting and stacking machine is constructed as follows. A shaft 46, journaled in brackets 47, supported in part by the supporting base 16, is driven from the crank shaft 30 by means of pairs of bevel gears 48 and 49 and a connecting shaft 50. A pinion 51 on the shaft 46 meshes with a pinion 52 on a short shaft 53. The shaft 46 carries a circumferentially grooved roller 54 and the shaft 53 carries a smooth roller 55 which engages the roller 54, the line of contact of said rollers being approximately in the plane of the strip of formed material as it leaves the forming machine. Tension between the rollers 54 and 55 is regulated by means of adjustable springs 56 on rods 57 secured in the bracket 47 and extending thru openings in the enlarged journal bearings 531 of the shaft 53. For the purpose of lifting

the upper roller to start the strip or for other purposes a hand lever 58 having a toe 59 which contacts with the upper surface of the bracket 47 is pivoted on a rod 60, connected with the bearings 531 of the shaft 53. As clearly shown in Figure 1 the toe 59 contacts with the bracket 47 at such a point that downward pressure on the handle 58 will rock the toe 59 under the lever pivot, and lift the pivot and with it the shaft 53 and roller 55.

It will be understood that while the rotation of the feed rollers 54, 55 is continuous the feeding movement of the element strip is intermittent. The strip is retained against movement during the forming operation of the head 23 by the stops 242, and at this time there is a slip between the feed rollers and the strip, each depression of the head 23 however not only depresses the forming plungers 26, etc. but also depresses the cutters 29 so that a portion of the edge of the strip equal to the distance between the dies 261 is cut off and when the head 23 and cutter 29 is raised the strip is advanced one step by the rollers 54, 55, until the forward edge of the untrimmed portion strikes the stop 242.

The devices for cutting the strip prepared in the forming machine and fed therefrom by the feed rollers 54, 55 comprises cutters supported in a face plate 61. The upper or fixed cutter 62 is held against the face plate by screws 63 passing thru slots 64, and is positively secured against upward movement by set screws 65 passing downward thru a laterally extending part 66 of the face plate 61. The lower or reciprocating cutter 621 is guided for vertical movement by guide plates 67 secured to the face plate 61. The mechanism for reciprocating the cutter 621 comprises bell crank 68 which carries a pin 69 adapted to engage a transverse slot 70 in the cutter 621. Bell crank 68 is pivoted at 71 and is held with the cutter 66 in depressed position by a spring 681 compressed between a part of the bell crank and the edge of the face plate 61. The bell crank carries a cam follower 72 adapted to be engaged by a cam 73 on a disc 74 carried by a short shaft 75, which is rotated by means of a worm and gear connection 76—77 with the shaft 46, which shaft, it will be recalled, is driven by crank shaft 20. It will be apparent that the cutter 621 will be actuated regularly and synchronously after a predetermined number of operations of the forming machine, and thus elements of a uniform length will be cut from the formed strip.

The mechanism for receiving the elements formed by the forming machine and cut off by the cutters is constructed as follows.

In alignment with the strip as it is advanced thru the machine is a frame comprising a base 78 uprights 79 and a top plate 80. Between the uprights 79 extends an elongated

70

115

120

125

130

element receiving table 81 which is supported on screws 82 extending thru threaded bosses integral with the table. The screws 81 are supported in bearings in the top plate 80, and 5 are provided above said plate with pinions 83 and 84, in mesh, with an intermediate idler 85. Pinion 84 meshes with a gear 86 having a one way connection with a short shaft carrying a bevel gear 87 which meshes with a bevel 10 gear 88 connected thru a universal joint 89 with the shaft 75, which it will be recalled is driven from the crank shaft 20. By means of the gearing just described the table 81 is lowered as successive elements are placed 15 thereon and the level of the top of the stack of elements on the table is kept at approximately the level at which elements are delivered by the cutters.

When the desired number of elements have 20 been placed on the table they may be compacted into a radiator by elevating the table by hand and pressing the stack between the table 81 and the top frame plate 80. To facilitate the manual lifting of the table for 25 this purpose, one of the screws 82 may terminate in a squared shank 90 adapted to receive a suitable handle by which the screws 82 may be turned.

Means are provided for automatically stopping 30 the motion of the machine when a predetermined number of elements have been made and stacked on the receiving table 81. For this purpose the lowering of the table 81 to a predetermined position is utilized to 35 actuate a clutch controlling device. A pin 91 is adjustably secured to the table 81. As the table is lowered in the operation of the machine to a position determined by the adjustment of pin 91, said pin engages a roller 92 40 carried by a pivoted latch 93 and rocks the latch about its pivot. A notch in the latch receives the end of an arm 94 secured to a shaft 95 controlled by a spring 98. Shaft 95 carries a finger 96 overlying a clutch pedal 97, which forms one end of a lever, pivoted 45 at 100, and connected with a link 101 which controls a suitable clutch associated with the driving means for the crank shaft 20.

The operation of the machine is as follows. 50 A roll of strip material 40 is placed on the supporting spindle 39. The thicker edge of the strip is turned toward the side of the machine adapted to receive it, and the supporting pin 441 is placed in the appropriate opening. If the strip leaves the roll at the top, pin 441 is placed in opening 44, while if the strip leaves the bottom of the roll opening 45 will be used. The end of the strip is then 55 passed under the roller 42 and the rod 43, over the die block 30, and between the feed rollers 54 and 55, the roller 55 being raised against the tension of springs 56 to permit the entrance of the end of the strip by pressing downward on the handle 58. The table 60 81 is then elevated to a position, slightly be-

low the level of the cutters 62, 621 by rotating the screws 82 by means of a handle applied to the squared shank 90.

The machine is then set in operation by depressing the clutch pedal 97 and securing it 70 in depressed position by the latching means 94, 95 and 96. As the plunger head 23 descends, the plunger 25 acts to flatten the strip ahead of the first plungers 26, and to straighten the strip from any drawing which has 75 been caused by the previous depression of the punches, the first plunger 26, forms a shallow depression in the strip. At the same time the cutting tools 29 notch the edges of the strip. When the plunger head 23 is raised 80 the spring plungers 31 lift the strip out of engagement with the dies 261 etc., permitting the feed rollers 54 and 55, which are continuously rotated, to advance the strip until the rear edge of the notch cut by cutting tool 29 85 engages the stops 242. This movement brings the depressions made by the first series of dies 26 into alignment with the second series of dies, which dies upon the second downward stroke of the plunger head 23 re-form the depressions to a narrower and deeper shape, at the same time that the first dies are forming another series of broad and shallow depressions. As the plunger head 23 continues to 90 reciprocate and the strip to be advanced, the depressions are successively re-formed in succeeding dies until they have assumed the proper shape. The punches 27 then remove the bottom from the depressions and the tubes are complete. The dies 28 and 281 95 perforate the strip intermediate the tubes, the cutters 29, already mentioned, trim the edges, and the strip thus formed passes thru the feed rollers 54, 55 and the aperture between the cutters 62, 621.

As the machine continues to operate, worm 77 on the shaft 46 rotates cam 74 and periodically brings cam 73 into engagement with follower 72, thus rocking the bell crank 68 to lift the knife 621 and cut the formed strip into 100 elements of uniform length. The elements thus formed are superposed on the receiving table 81, said table being slowly lowered thru the rotation of screws 82 by pinions 83, 84 etc., to keep the top of the stack of elements at approximately the level of the cutters, as is more completely described in my copending application Serial No. 641,850 filed May 28, 1923.

The cam pin 91 having previously been set 115 to engage the latch roller 92 when the table 81 has been lowered thru a distance corresponding to the desired number of elements, i. e. when the number of elements necessary to form a radiator have been placed on the 120 table the latch 93, will be rocked by pin 91, to release the arm 94 and with it the clutch pedal 97, thus stopping the machine. The table 81 with the loosely stacked elements thereon is then raised by manually rotating the 125 130

screws 82 and the stack of elements is compacted into the radiator, shown in Figure 11. This radiator is then removed, the table is restored to initial position and the machine again set in operation. Figure 12 shows on an enlarged scale the appearance of the nested tubes in the finished radiator.

My invention is not to be considered as limited to the precise construction and method of operation hereinbefore described, but is to be construed as conferring all equivalent machines and processes coming within the scope of the appended claims.

I claim:

1. The method of forming a radiator core from flat sheet material, which comprises, forming a plurality of integral single walled cup shaped projections from said sheet, perforating the bottoms of said projections, assembling strips of said sheet material with the perforated projections of one strip registering with the perforated projections of the adjacent strip, and pressing said strips together, with the projections of adjacent strips in telescoping relation and in permanent engagement.

2. The method of forming a radiator core, which comprises forming a plurality of rows of integral tapered cup shaped projections from a flat strip of metal, perforating the bottoms of said projections, cutting said strip into sections and assembling said sections in superposed relation with the bottom of the projections of one section extending into and pressed into permanent engagement with the top of the projections of the adjacent section to form fluid conduits through the core.

3. The method of forming a radiator core from a flat strip of metal, which comprises forming large diameter shallow depressions in said strip progressively re-forming said depressions into smaller diameter deeper depressions perforating the bottom of said depressions after the forming is completed and assembling sections of said formed strip in superposed relation with the projections of one section extending into the projections of the adjacent section to form water conduits through the core.

4. The method of making a radiator which comprises the steps of forming broad shallow depressions in an undivided strip of sheet material, progressively re-forming said depressions into recesses of a desired depth and shape, punching the bottom from said recesses to form tubes and superposing sections of the material thus formed.

5. The method of making a radiator which comprises the steps of forming round tubular projections on an undivided strip of sheet material without materially weakening said sheet, superposing sections of the strip thus formed with the tubular projections of one section extending into the tubular projec-

tions of the adjacent section, and compacting the stack of superposed sections.

6. The method of making a radiator which comprises the steps of forming tubular projections on an undivided strip of sheet material without materially changing the thickness of said sheet and superposing elements of the strip thus formed with the projections of adjacent elements in mutually engaging relation.

7. The method of making a radiator comprising the steps of forming shallow depressions in an undivided strip of sheet material, re-forming said depressions into recesses of a desired size and depth without materially altering the thickness of the material punching the bottoms from said recesses to form tubes and superposing sections of the strip thus formed with the tubes of adjacent sections in engaging relation.

8. The method of making a radiator core comprising the step of forming shallow depressions in an undivided strip of sheet material, thereby reducing the width of said strip, re-forming said depressions into projections of a desired shape and size without further reducing the width of said strip, punching the bottoms from said projections to form tubes and superposing sections of the strip thus formed.

9. The method of radiator construction comprising forming shallow depressions in an undivided strip of sheet material, thereby reducing the width of said strip, progressively re-forming said depressions into tubular projections trimming the strip to a uniform width and assembling the strip thus formed into a heat transfer section.

10. In the manufacture of radiator cores, the method which comprises, producing in a piece of sheet metal a plurality of shallow depressions of predetermined outline, then increasing the depth of the depressions and simultaneously decreasing their outline in a number of steps, the change in the dimensions of the depressions being so graduated that the metal is not appreciably thinned in the depressions, then punching out the material of the bottom of the depressions, to form a plurality of tubes projecting from the sheet, and assembling sections of the sheet so formed in superposed relation with the tubes of one section extending into the tubes of the adjacent section to form water conduits through the core.

11. In the manufacture of radiator cores, the method which comprises, producing in a strip of sheet metal a plurality of shallow depressions of predetermined outline, increasing the depth of these depressions and simultaneously decreasing their outline, producing a plurality of shallow depressions adjacent the deepened depressions, and then further increasing the depth and decreasing the outline of both sets of depressions, the

change in the dimensions of the depressions being so graduated that the metal is not appreciably thinned in the depressions, perforating the bottom of said depressions and assembling sections of the strip so formed in superposed relation with the depressions in alignment.

12. In the manufacture of radiator cores, the method which comprises, producing in a strip of sheet metal a plurality of shallow depressions of predetermined outline, increasing the depth of these depressions and simultaneously decreasing their outline, producing a plurality of shallow depressions adjacent the deepened depressions, then further increasing the depth and decreasing the outline of both sets of depressions, punching out the material at the bottom of the depressions, the walls of the depressions being in the form of a plurality of tubes projecting from the sheet, cutting the strip so formed into sections, assembling said sections in superposed relation with the depression in alignment and pressing the sections together.
13. In the manufacture of radiator cores, the method which comprises, producing in a strip of sheet material a shallow centrally arranged initial depression to narrow the strip, then producing a similar depression at either side of the first depression, and thereafter increasing the depth of the depressions and simultaneously decreasing their outline, perforating the bottoms of said depressions and assembling sections of the strip so formed in superposed relation with the ends of the depressions telescoping together.

In testimony whereof I have affixed my signature to this specification.

JOHN KARMAZIN.
